G. E. McDONALD ET AL

FIRE EXTINGUISHER

Original Filed Nov. 28, 1921

Inventor:
George E. McDonald, Thomas T. Taylor
By their Attorney, Geo. F. Heath

UNITED STATES PATENT OFFICE.

GEORGE E. McDONALD AND THOMAS E. TRAYNOR, OF JERSEY CITY, NEW JERSEY.

FIRE EXTINGUISHER.

Application filed November 28, 1921, Serial No. 518,215. Renewed March 21, 1924.

To all whom it may concern:

Be it known that we, GEORGE E. McDONALD and THOMAS E. TRAYNOR, citizens of the United States, and both residents of Jersey City, county of Hudson, and State of New Jersey, have invented certain new and useful Improvements in Fire Extinguishers, of which the following is a specification.

10 Our improvements relate to the class of portable suspensible containers for fire-extinguishing liquid which is to be released automatically by the melting of fusible sealing matter; and are designed to protect 15 such extinguishing liquid against loss by evaporation, and from deterioration by free contact with the atmosphere, while providing for the precipitate discharge of the liquid by atmospheric and hydrostatic pressure upon the opening up of the discharge ports by the melting of the fusible seal substantially as hereinafter set forth,—the invention consisting in the specific combination and arrangement of parts and appurtenances described and claimed, and a distinctive feature being the use of a float valve which normally prevents communication with the atmosphere but which opens automatically to admit air to replace, and facilitate the discharge of, the extinguishing liquid when the discharge ports are unsealed.

In the accompanying drawings, Fig. 1, is a top view of our improved fire extinguisher;

Fig. 2, is an end elevation of the bottom thereof;

Fig. 3, is a central longitudinal section, with the contained extinguishing liquid, the discharge orifices being sealed by a fusible substance;

Fig. 4, is a view like unto Fig. 3, illustrating the discharge of the extinguishing liquid through the unsealed discharge orifices.

45 Our device consists of a container C, preferably, although not necessarily, of cylindrical form, closed at the lower extremity by a concavo-convex bottom b, the convexity being external. Within the internal cross 50 sectional area of the body portion of the container C, said concavo-convex bottom b, is formed with an annular series of discharge orifices d, closed normally by a fusible material f, adapted to melt at a relatively low 55 temperature as compared with combustive heat generally, but of sufficient strength and

tenaciousness to support the column of fire-extinguishing liquid within said container under ordinary atmospheric conditions and temperatures. 60

The upper extremity of the container C, is closed by a head h, formed with a filling neck h', adapted to receive a screw cap s, (indicated in dotted lines in Fig. 3) or any other means of closure, when desired for storage or transportation. When the extinguisher is installed for service the closure s, is removed so as to admit of free communication with the atmosphere. 65

The head h, of the container or reservoir C, is also provided with a loop-handle h², which likewise affords convenient means whereby the apparatus may be suspended in situ for use.

In alignment with the inlet i, in the head h, and with the neck h', as shown in Figs. 3 and 4, we position our float valve v, said valve v, being preferably formed with a facing v', of rubber, felt, or other suitable material, adapted to make an air tight contact 70 with the edges of the inlet i, when pressed thereagainst, as in Fig. 3. The valve v, is affixed to the upper end of a rod v², of suitable length, slidably mounted on and between bearing bracket arms c, c, attached to 75 the inner side wall of the container C, said bearing bracket arms c, c, being so spaced apart as to afford the necessary support and extent of movement for said valve rod v², as will be seen by a comparison of Figs. 3 and 4. Attached to the lower extremity of 80 the valve rod v², is a float v³, of any desired or suitable form and construction, that indicated in the drawings being a hollow cylindrical sealed compartment which will displace much more than its own weight of the fire-extinguishing liquid e, so that when immersed in said liquid e, as in Fig. 3, it will 85 force and hold the valve v, in contact with the top plate h, with sufficient pressure to 90 insure a practically air tight seal, and exclude the atmosphere. 95

When, however, the melting of the fusible filling f, of the discharge orifices d, d, in the bottom b, of the container C, permits of 100 the escape of the fire-extinguishing liquid e, therefrom, the diminution of hydrostatic pressure upward against the float v³, and the creation temporarily of a partial vacuum by the lowering of the liquid level within 105 the upper part of the container immediately causes the release of the valve v, and the es- 110

2
tablissement of free communication through
the vent *i*, with the atmosphere.

Hence it will be seen that while, by our improved construction and arrangement of 5 parts, we guard the fire extinguishing liquid against atmospheric absorption and evaporation, and against deterioration by oxidation by free contact with the atmosphere, we nevertheless facilitate the discharge of the 10 said fire extinguishing liquid upon occasion by providing for a complete balance of atmospheric pressure both above and below the column of liquid within the container, as clearly indicated in Fig. 4, of the drawings.

In this connection it may be stated that the protection thus afforded against chemical reactions within the container is especially important where the fire extinguishing liquid contains carbon-tetra chloride, and other oxidizable substances held in solution therein, as is usually the case in fire extinguishers of analogous types to ours,—our invention being designed primarily to isolate and protect the solution in this respect, and prevent concentration and diminution of volume by evaporation while insuring practically instantaneous responsive action in emergency.

30 Furthermore our device, considered in a unitary sense, is simple and inexpensive, and not liable to derangement if ordinary care is exercised in the manipulation and installa-

tion thereof,—the closure *s*, providing for convenient transportation and storage, and 35 the simple act of its removal upon installation of the container rendering the device immediately available and operable.

What we claim as our invention and desire to secure by Letters Patent is,

40 A fire extinguishing device of the character designated, comprising a liquid container formed with discharge apertures in its lower extremity, fusible sealing material normally closing said discharge apertures, 45 an inlet and vent aperture in the upper portion of said container, a filling neck coincident with said inlet and vent aperture, a closure for said filling neck, and a float valve 50 arranged to close said inlet and vent aperture by means of hydrostatic pressure exerted by the liquid contents of the container and free to gravitate away from said vent when said fusible material melts to balance atmospheric pressure both above and below 55 the column of liquid in said container, and a guide for the stem of said valve arranged to limit the downward movement thereof, substantially in the manner and for the purpose described.

GEORGE E. McDONALD.
THOMAS E. TRAYNOR.
